UNITED STATES PATENT OFFICE

CHARLES J. KUMMER, OF SHEBOYGAN, WISCONSIN, ASSIGNOR TO SHEBOYGAN MACHINE COMPANY, OF SHEBOYGAN, WISCONSIN, A CORPORATION OF WISCONSIN

SANDER FEED MECHANISM

Application filed March 24, 1930. Serial No. 438,427.

The invention relates to sanding machines and more particularly to feeding mechanism therefor.

Sanding machines as usually constructed have a feeding mechanism immediately adjacent the sanding roll for carrying the work into the machine under the guidance of and with the help of the operator. With such devices it is necessary for the operator to place the work on the feeding mechanism and get it started into the machine as the feeding mechanism in and of itself will not carry it into the machine and because of this only one piece of stock can be presented to the machine at a time and the capacity of the machine is limited because of this and the extra duty imposed on the operator of assisting this mechanism in feeding the stock into the machine. The object of the present invention is to provide an auxiliary, power-operated feed for sanders used in conjunction with the usual feed mechanism with which said machines are provided, whereby the operator is relieved of his usual duties of assisting the feed mechanism. More particularly the invention comprises a power-driven feed roll which is adjustable relative to the usual feed mechanism to accommodate different lengths of stock and which in conjunction with said usual feed mechanism permits stacking of the stock at the entrance end of the machine and the successive feeding of the pieces at the bottom of this stack into the machine.

The invention further consists in the several features hereinafter set forth and more particularly defined by claims at the conclusion hereof.

In the drawings Fig. 1 is a detail plan view of a sanding machine equipped with the feeding means embodying the invention;

Fig. 2 is a side elevation view thereof;

Fig. 3 is an end elevation view thereof;

Fig. 4 is a detail vertical sectional view taken on the broken line 4—4 of Fig. 2.

Referring to the drawings the numeral 6 designates the main frame of a sanding machine, 7 the rotating sanding drum journaled in vertically adjustable bearings 8 and rotated by any suitable drive mechanism from any suitable source of power, these details

not being shown as they form no part of the present invention. Various feed mechanism adjacent the sanding drum are used to carry the work under the sanding drum for accomplishing the sanding operation and as illustrative of one known form of feed mechanism for this purpose I have shown a portion of an endless conveyor or apron 9, one end of which runs over a power-driven pulley on a shaft 10 journaled in the arms 11 forming part of the framework of the machine, this apron being formed in known manner of a plurality of articulated slats 12, each having a plurality of rubber pads 13 secured thereto by screws 14. As the details of construction of this apron are known and do not of themselves form the subject-matter of this invention and as other equivalent means of known construction, arranged at the entrance end of the sander, may be used in conjunction with the power feed hereinafter described, further description of this feed mechanism or the specific showing of other feed mechanism known to the art is deemed unnecessary.

My invention comprises the association or combination with the usual feeding mechanism for sanding machines operating on the forward end portion of the stock, of an auxiliary, power-operated feed mechanism and in this connection a construction that may be readily attached to sanding machines now in use. For this purpose I provide an auxiliary frame of spaced frame members 15 bolted to the front of that part of the frame in which the shaft 10 is journaled by bolts 16 and having dove-tailed, longitudinally extending guideways 17 formed therein in which the matching bases 18 of the roller supports 19 are slidably mounted and adjustable to different positions. An auxiliary feed roller 20, as shown in Fig. 4, has shaft extensions 21 journaled in the supports 19 and one of these extensions carries a sprocket 22 engageable with a chain 23 passing over an idler sprocket 24 at one side of the auxiliary frame and over the driven sprocket 25 fixed to the shaft 10 so that the drive for the regular feed mechanism of the machine drives said roller 20.

The supports 19 are moved along the supporting guides and adapted to be held in the desired position of adjustment thereon by forming part of each base 18 with rack teeth 26 meshing with a gear 27. The gears 27 are mounted on a manually-operated shaft 28 journaled in the frame members 15 and provided with a hand-wheel 29. The top face of the roller 20 is substantially level with the top faces of the pads 13.

With this construction the operator can adjust the position of the auxiliary feed roller along the ways of its supporting frame so that it is positioned adjacent the outer ends of the stock, the adjustment provided taking care of the longest stock, and when so positioned it will be noted from Fig. 2 that when the board A, which is shown going through the machine, has entered it fully the board B is free to drop down onto the feed apron at its forward end and upon the roller 20 at the rear end so that the traction force of this roller 20 will aid the apron or other usual feed mechanism in carrying the board into the machine. It will also be observed that this arrangement permits the above-described stacking, since the power feed herein provided engages the lowermost board and obviates the necessity of the operator's holding down on the forward end of the board to get it started into the machine.

To safeguard the operator and keep material from the roller until the previous board falls into place, a transversely extending, angled guard bar 30 is secured at its ends to the supports 19 and serves as a stop to prevent the operator getting his fingers in between the stock and the roller.

In order to handle the shortest pieces of stock, I have provided a power-operated feed-roller 31, whose shaft 32 is journaled in the frame portion 11 of the machine and one end of which carries a sprocket 33 engaging the chain 23, this roller being arranged as closely as possible to the feed apron to assist the same in feeding the stock into the machine.

I desire it to be understood that this invention is not to be limited to any particular form or arrangement of parts except insofar as such limitations are included in the claims.

What I claim as my invention is:

1. In a sanding machine, the combination with the feed mechanism engageable with the forward end portion of the stock to feed it into the machine, of auxiliary, power-driven feed mechanism engageable with the outer end portion of the stock for assisting in feeding the stock into the machine, and means for adjusting the position of said auxiliary feed mechanism for its action on different lengths of stock.

2. In a sanding machine, the combination

with the main feed mechanism of the machine, of an auxiliary feed-roller adjustable toward or away from the main feed mechanism to accommodate different lengths of stock and so as to support the stock at its end portions on said mechanism and roller, and power-operated means for driving said feed-roller in any position of adjustment.

3. In a sanding machine, the combination with the main feed mechanism of the machine, of an auxiliary feed-roller adjustable toward or away from the main feed mechanism to accommodate different lengths of stock and so as to support the stock at its end portions on said mechanism and roller, manually-operated means for moving said roller to its desired adjusted portion, and power-operated means including an endless drive element operatively connected to said roller for driving the same in any position of adjustment.

4. In a sanding machine, the combination with the main feed mechanism of the machine, of an auxiliary feed-roller adjustable toward or away from the main feed mechanism to accommodate different lengths of stock and so as to support the stock at its end portions on said mechanism and roller, and power-operated means including a drive chain and a sprocket carried by said roller and engageable with said chain in any position of adjustment of said roller.

5. In a sanding machine, feed mechanism comprising power-driven feed elements engageable with the forward and rear portions of the stock for feeding the stock into the machine and whereby the stock may be stacked at the entrance end of the machine and the lowermost piece of stock successively fed into the machine, one of said elements being longitudinally adjustable relative to the other to accommodate stacks of stock of different lengths in their end-supported relationship to said feed elements.

In testimony whereof, I affix my signature.

CHARLES J. KUMMER.
